[57] ABSTRACT

A container fabricating machine having a forming mechanism for erecting and bottom sealing paper-board container blanks and a filling mechanism for filling and top-sealing the bottom formed containers. The bottom forming mechanism includes a plurality of mandrels mounted on a spindle that are intermittently driven past a plurality of the mechanism's operating stations, the bottom formed containers being discharged from the mechanism in a downwardly inclined direction and a transfer mechanism for gripping the bottom of the discharged containers and pivoting them to an upright position. The filling mechanism includes a feeding mechanism that receives the containers from the transfer mechanism and grips all four corners of the bottom formed containers while advancing them through the filling mechanism's filling and sealing operations and that is readily adjustable to accommodate containers of various base sizes without disturbing the machine's overall synchronization.

CONTAINER FABRICATING MACHINE

This invention relates to a container fabricating machine and, more particularly, to a new and improved machine for automatically, efficiently, and more accurately forming, filling, and sealing gabled-top, plastic-coated paperboard containers.

Many types of container fabricating machines have been provided in the past for plastic-coated paperboard containers. Such machines have found particular, but not exclusive, utility in the dairy industry where paperboard containers of various sizes are provided in the form of flattened, tubular blanks and are erected, filled, and sealed directly at the dairy for immediate consumer distribution. Because of the many different size containers that are used and the wide diversity in volume requirements, both single size, high production rate machines as well as more universal, but low production rate machines have been provided in the past to meet the individual needs of different dairy operations.

In most all of these machines, however, there are generally two basic mechanisms: a container forming mechanism for erecting and bottom sealing the container blank and a container filling mechanism for filling and top sealing the bottom formed container. Therefore, it has been necessary with such machines also to provide a mechanism for transferring the container between the forming and filling mechanisms. In addition, the transfer mechanism is required to remove the bottom formed container from the forming mechanism, turn the container over into an upright position and also about its longitudinal axis, and align and synchronize the transferred container with the filling mechanism.

All of these operations tend to slow down the speed of the machine and increase the manipulations required which necessarily reduces the efficiency, economy, and accuracy of the overall machine operation. Further, and when the machines are constructed for use with containers of varying sizes, it is also necessary to provide means for adjusting not only the transfer mechanism and the forming and filling mechanisms so that they may fit the different size containers, but also adjustments must be made in the synchronization between the mechanisms in order to produce a properly formed container.

The present invention, therefore, is directed to a new and improved container fabricating machine that transfers containers between forming and filling mechanisms and that feeds the containers through the filling mechanism in a more accurate, precise, and efficient manner than heretofore has been provided and that is capable of accommodating containers of varying sizes with a minimum of mechanical adjustment and without disturbing the machine's overall synchronization.

Accordingly, in one embodiment of the present invention there is provided in a container fabricating machine for forming, filling, and sealing tubular container blanks having top and bottom foldable closure panels, a container forming mechanism including a supporting structure, a spindle mounted to the structure for rotation about a horizontal axis, and means for rotating the spindle with an indexing motion. A plurality of mandrels are mounted on the spindle and extend

radially therefrom for receiving and holding a container blank in an open position.

Means are further provided which define a plurality of machine stations spaced about the axis of rotation of the spindle for sequential registration with the mandrels. The machine stations include container blank erecting means for erecting a blank into an open-ended tubular form and for feeding the opened blank onto a mandrel on the spindle; bottom forming means for breaking, heating, folding, and sealing the bottom closure panels of the container blank; and container removing means located in a lower quadrant of the path of rotation of the spindle for removing a bottom formed container off the mandrel in a downwardly inclined direction.

Transfer means are further provided for receiving the container in its downwardly inclined position and for gripping and pivoting the container upwardly through an angle of less than 90° to an upright position.

In accordance with a preferred embodiment of the present invention, the transfer means includes a transfer arm pivotally mounted for movement between a first position coextensive with the inclined axis of the container after it is moved from the container forming mechanism and a second vertical position. A suction cup is mounted on one end of the transfer arm for receiving and gripping the bottom of the container, and actuating means are provided for pivoting the arm and the container between said first and second positions.

Preferably, means are further provided for selectively rotating the transfer arm 90° about its axis as it moves between its first and second position so that the container can be rotated 90° about its longitudinal axis if necessary to properly position it with the filling mechanism.

In accordance with another embodiment of this invention and preferably for use in combination with the above described forming and transfer mechanisms, there is provided in a container filling mechanism a new and improved feeding mechanism for advancing the bottom formed containers with a step-by-step indexing motion through the mechanism's filling and sealing operations. The feeding mechanism of this invention includes a supporting surface for supporting the bottom of the containers as they are advanced through the filling mechanism and a pair of endless chain assemblies arranged in spaced, parallel relationship on opposite sides of the direction of travel of the container.

A plurality of conveyor blocks are mounted on the chain assemblies in opposed, transverse registration for movement therewith, a first pair of opposed blocks each having corner means for engaging one of the leading corners of the container and the next succeeding pair of opposed blocks each having corner means for engaging one of the trailing corners of the container whereby the container is firmly gripped by its four corners and advance through the filling mechanism by adjacent pairs of opposed blocks.

Preferably, each of the blocks is provided with a plurality of corresponding corner means and the chain assemblies are adjustable toward and away from each other to accommodate the feeding mechanism to containers of different base sizes.

It is to be understood that both the foregoing general description and the following detailed description are exemplary and explanatory but are not restrictive of the invention.

The accompanying drawings which are incorporated in and constitute a part of the specification illustrate several embodiments of the invention and together with the description serve to explain the principles of the invention.

Of the drawings:

FIG. 1 is a perspective view of a container fabricating machine embodying the principles of the present invention;

FIG. 2 is a side elevation view of the fabricating machine with the covers removed and schematically illustrating the relationships of the various operating parts;

FIG. 3 is a schematic view illustrating successive steps of forming, filling, and sealing in the container fabricating machine of the present invention;

FIG. 4 is a side elevation view of a mandrel for holding the container blanks;

FIG. 5 is a sectional view taken along the line 5—5 of FIG. 4;

FIG. 6 is a perspective view of the container blank erecting and feeding mechanism;

FIG. 7 is a plan view of the bottom closure panel pre-breaking mechanism;

FIG. 8 is a sectional view of the pre-breaking mechanism taken along the line 8—8 of FIG. 7;

FIG. 9 is a perspective view of the bottom folding rails and their relationship with the first of the bottom sealing presses;

FIG. 10 is a perspective view of the second bottom sealing press and top closure panel pre-breaking mechanism;

FIG. 11 is a sectional view taken along the line 11—11 of FIG. 10;

FIG. 12 is a view of the surface of the press plate;

FIG. 13 is a perspective view of the container removal station of the forming mechanism;

FIG. 14 is a top plan view of the mechanism shown in FIG. 13;

FIG. 15 is a sectional view taken along the line 15—15 of FIG. 14;

FIG. 16 is a side elevational view of the transfer mechanism for transferring bottom formed containers from the forming mechanism to the filling mechanism;

FIG. 17 is a partial sectional view taken along the line 17—17 of FIG. 16;

FIG. 17A is a sectional view taken along the line 17A—17A of FIG. 16;

FIG. 18 is a top plan view of the feeding mechanism in the filling mechanism;

FIG. 19 is an enlarged side sectional view taken along the line 19—19 of FIG. 18;

FIG. 20 is an enlarged sectional view of one of the chain assemblies and taken along the line 20—20 of FIG. 18;

FIG. 20A is an enlarged side sectional view taken along the line 20A—20A of FIG. 18;

FIG. 21 is a fragmentary sectional view taken along the line 21—21 of FIG. 18 and showing the driving means for the chain assemblies;

FIG. 22 is a perspective view of the loading end of the filling mechanism;

FIG. 22A is a fragmentary top plan view of the loading end of the filling mechanism and showing the locking arms for squaring up the side walls of the container;

FIG. 23 is an enlarged and fragmentary top plan view of the feeding mechanism and showing the relationship of the chain assemblies for use with smaller size containers;

FIG. 24 is a view similar to FIG. 23 and showing the feeding mechanism adjusted for use with large size containers;

FIG. 25 is a perspective view of one of the plurality of conveyor blocks used in the feeding mechanism;

FIG. 26 shows a tubular container blank in flattened form;

FIG. 27 is an end view of the blank of FIG. 26;

FIG. 28 is a perspective view of the container blank in an open and upside-down position;

FIG. 29 is a perspective view similar to FIG. 28 showing the container's bottom closure panels sealed in place;

FIG. 30 is a perspective view of the container blank with the bottom formed in an upright position; and

FIG. 31 is a perspective view of the container after it has been formed, filled, and sealed.

Reference will now be made in detail to the present preferred embodiments of the invention examples of which are illustrated in the accompanying drawings.

For the purpose of clarity and simplification, only those parts of the various mechanisms for forming, filling, and sealing the container blank that are essential to an understanding of the present invention have been illustrated in the drawings.

CONTAINER

The machine of the present invention is particularly adapted to form, fill, and seal plastic-coated paper-board containers described, for example, in U. S. Pat. No. 3,120,333 and 3,120,335. The disclosures of these patents are incorporated herein by reference, and reference should be made to these patents for a more complete description of the containers which may be formed, filled, and sealed by the machine of the present invention.

These containers have particular utility for the packaging of milk, and the present invention will be described as it relates to a milk packaging operation, but it is to be understood that the machine of the present invention may also be utilized for the packaging of other materials in similar containers. Further, the machine of the present invention can readily be used for the forming, filling, and sealing of different size containers of varying lengths and cross-sectional dimensions.

With reference to FIGS. 26 and 31, there is illustrated a typical container 10 for use with the machine of the present invention. Container 10 is generally supplied in flattened form, as shown in FIGS. 26 and 27 and when opened, as shown in FIG. 28, is a tubular body 12 of generally rectangular cross section. Tubular body 12 includes a first pair of opposed side walls 13 and a second pair of opposed side walls 15, interconnected along their vertical sides to walls 13. Bottom closure panels 14 and top closure panels 16 for the container are formed from integral extensions of the container's side walls and are folded and sealed in such a

manner as to provide a closed container, as shown in FIG. 31.

Bottom closure panels 14 includes a pair of opposed bottom gusset panels 18 and a pair of opposed bottom flaps 20, integrally connected along their vertical sides to bottom gusset panels 18. Bottom gusset panels 18 include a triangular portion 22, separated from side walls 13 by a fold line 30, and a pair of triangular fold-back portions 24 separated from triangular portion 22 by fold lines 26.

Bottom flaps 20 are separated from container side walls 15 by fold lines 28 and the projecting edge 32 of one bottom flap 20' is chamfered slightly on both ends at 33, defining a tuck-in extension that is inserted under a corresponding projection edge 34 defining a tuck-out extension on the other bottom flap 20''.

Thus, when the bottom is formed, triangular portions 22 of opposed gusset panels 18 fold inwardly toward one another and their associated pairs of fold-back, triangular portions 24 fold back against the inner faces of bottom flaps 20. The tuck-in edge 32 on bottom flap 20' is then inserted between the inner face of bottom flap 20'' and the fold-back portions 24 of gusset panels 18 and the edge 34 of the tuck-out flap overlies the edge 32 of bottom flap 20'. When fully folded in the manner described, the bottom closure panels are pressured flat and heat sealed in this position to form a bottom for the container, as shown in FIG. 29.

The top closure panels 16 are similar to bottom closure panels 14 and include, as shown in FIG. 30, a pair of opposed top gusset panels 40 and pair of opposed roof closure panels 42 inter-connected along their vertical sides with top gusset panels 40. Gusset panels 40 include triangular portion 44 separated from side walls 13 by a fold line 45, and a pair of fold-back triangular portions 46 separated from triangular portion 44 by fold lines 47. Roof panels 42 are separated from side walls 15 by fold lines 49, and projecting from the outer lateral edge of each roof closure panel 42 is a sealing flap 48 separated from the roof panel by a fold line 50.

When the top closure is formed, triangular portions 44 of top gusset panels 40 fold inwardly toward one another and their associated pairs of triangular fold-back portions 46 fold back against the inner face of roof panels 42, thus bringing sealing flaps 48 into abutting relationship and forming a top to the container having a gabled configuration, as shown in FIG. 31.

The top closure of the container also includes an extensible pouring spout which is defined by one of the gusset panels and a pair of score lines 52 on adjacent sides of both roof panels 42, as is well known to those skilled in the art.

The container is generally supplied in flattened form, as shown in FIGS. 26 and 27, with side seam flap 54 already sealed in place and having a first pair of folded corners 56 and two opposed longitudinal score lines 58 for forming a second pair of folded corners when the container is in open position, as shown in FIG. 28. The machine of the present invention, therefore, is particularly designed to produce finished and filled containers from these flattened blanks, but it will be obvious to one skilled in the art that containers pre-fabricated to a greater degree can also be used with certain embodiments of the present invention.

GENERAL MACHINE DESCRIPTION

The present invention provides a new and improved container fabricating machine for erecting, filling, and sealing these flattened container blanks in a simplified, efficient, and economical manner.

As shown in FIG. 1, the container fabricating machine consists generally of a container forming section 60 and a container filling and sealing section 62. The container forming section 60 receives a plurality of flattened container blanks 10, as shown in FIG. 26, and feeds them in sequence on an automatic and continuous basis through the machine's bottom forming operation. Upon completion, the bottom formed containers are discharged from container forming section 60 in a downwardly inclined direction and are transferred in an upright position to filling and sealing section 62 where they are filled and sealed, as shown in FIG. 31, and then discharged. The present machine, as such, represents an improvement over that shown in U. S. Pat. No. 3,364,826 to Austin et al., dated Jan. 23, 1968 and entitled Carton Forming Apparatus; and U. S. Pat. No. 3,465,494 to Garrett et al., dated Sept. 9, 1969, and entitled Filling and Sealing Machine.

As shown in FIG. 1, container fabricating machine 60 is generally enclosed by a covering 64 having appropriate panels and doors for access to interior portions of the machine. With reference to FIG. 2, where the machine is shown with coverings 64 removed, the machine includes a supporting or frame structure, generally 66, having legs 68 for supporting the machine's operating mechanisms and is supplied with electrical power, compressed air, and hydraulic fluid from appropriate sources (not shown). The operator's control panel 67 is located on top of filling section 62 for easy access by the operator.

CONTAINER FORMING MECHANISM

In accordance with the invention, a container forming mechanism, generally 69, is provided in container forming section 60 of the machine and includes a spindle 70 journaled in suitable bearing members (not shown) supporting structure 66 about a horizontal axis 74 so that the spindle rotates in a vertical plane. Spindle 70 has a hub 76 and a plurality of arms 78 extending radially outward therefrom at equal angles of separation. Each arm 78 mounts and forms a part of a mandrel 80, as best seen in FIGS. 4 and 5, for internally supporting a tubular container blank during the machine's bottom forming operations. Each of the mandrels are identical in structure and are shown and described in detail in U. S. Pat. No. RE 26,699 to Austin, Jr., et al., dated Oct. 28, 1969, and entitled Carton Forming Mandrel. For a more complete description of mandrels 80, reference should be made to this patent which is assigned to the assignee of the present invention and the disclosure of which is herein incorporated by reference.

Briefly, and with reference to FIGS. 4 and 5, each mandrel 80 includes a base 82 and an arm 78 having an elongated slot 84 therein. A sleeve structure, generally 86, is composed of a pair of shoulder halves 88 which are substantially identical in form and connected together by suitable connecting bolt 90 extending through upper shoulder 88, slot 84 in arm 78 and threaded into lower shoulder 88''.

Sleeve structure 86 is slidably mounted in groove 89 in mandrel arm 78 and defines an outer edge 82 against which the top closure panels 16 of the container blank are to be broken. An end cap 92 is secured to the outer extremity of arm 78 against which bottom flaps 14 of the container are to be creased. The mandrels are adapted to accommodate various size containers from half pint through half gallon sizes and end caps 92 come in various sizes to accommodate the various cross sections of the container blanks.

The outer edges 82 of slidable shoulder halves 88 form a composite rectangular structure when mounted to arms 78 (see FIG. 5) and are the same rectangular dimension of a larger end cap (not shown) for relatively larger size containers. An inner edge 96 on shoulder halves 88 defines a similar rectangular structure of the same size as smaller end cap 92 for relatively smaller size containers.

Mounted to base 82 of mandrel 80 are projecting fingers 98 which engage top closure panels 16 of the larger size containers and similar fingers 100 project from each shoulder 88 to perform the same function on a smaller size container 10, as shown in phantom in FIG. 4. Each of the mandrels 80 are identical in construction and adapted to mount the various size container blanks to be formed on the present machine.

In keeping with the concept of this invention, machine cycling means are provided for rotating spindle 70 and attached mandrels 80 about horizontal axis 74 with an indexing motion for sequential registration of each of mandrels 80 with a plurality of machine stations for erecting the container blanks, breaking, heating, and sealing the bottom closure panels, discharging the formed container and for actuating and controlling mechanisms at these stations for carrying out the necessary machine operations. As embodied, this machine cycling means includes an indexing device (not shown) such as a barrel cam, manufactured by the Commercial Cam and Machine Company, Chicago, Illinois, and connected to the main power shaft of spindle 70 for rotating the spindle and the attached mandrels in the prescribed manner. The machine cycling means further includes pneumatic control circuits for actuating hydraulic cylinders and other mechanisms at the various machine stations as more fully described below.

With a spindle having eight (8) radial arms 78 and eight (8) corresponding machine stations, for example, as shown in FIGS. 2 and 3, the machine cycling means should rotate spindle 70 one-eighth (1/8) of a revolution in a timed manner to periodically and sequentially index each of mandrels 80 with each of the machine stations. Further, a suitable dwell time should be provided at each station to permit the necessary operations to be performed on the container blank. The machine cycling means are conveniently controlled by the operator from control panel 67 on the outside of the machine.

Machine cycling means suitable for use with the present invention are well known to those skilled in the art and are shown and described, for example, in U. S. Pat. Nos. 3,196,760 to Terry; 3,307,325 to Garrett et al; 3,364,826 to Austin et al; and 3,383,829 to Dudson et al and the disclosure of these patents is incorporated herein by reference.

Briefly, in operation and as best shown in FIGS. 2 and 3, a flattened container blank 10 is inserted into a container erecting means 102, positioned at erecting station "A" by the machine operator or by other suitable means with top closure panels 16 toward axis 74 of the spindle. At station "A" the container is erected into open-ended tubular form and fed onto a mandrel located at that station.

After the container blank is positioned on the mandrel, spindle 70 indexes the mandrel in a counter-clockwise direction to a bottom panel breaking station "B" where means are provided for breaking the fold lines on the bottom closure panels 14 of the container. Meanwhile a second container blank is erected and fed onto the next mandrel 80' which has now been indexed to loading station "A."

On a second and third index, the container is rotated to heating stations "C" and "D" where means are provided for heating the coating on bottom closure panels 14. A fourth index moves the panels 14 of the container through folding rails 142 and 144 where the heated panels are folded into place and then to a sealing station "E" where the folded panels are sealed in place.

On a fifth index the container is then given a fifth index to a second bottom sealing station "F" where the folded bottom panels 14 are again pressed shut to insure a complete sealing, and the fold lines of top closure panels 16 are also broken.

On a sixth index, the container rotates to a discharge station "G" where the bottom formed container is removed from a mandrel 80 on spindle 70 in a downwardly inclined direction and on the seventh index the mandrel rotates to a cooling station "H." On the last and eighth index, the mandrel rotates back to a loading position "A" to receive another container blank and start the cycle over again.

Thus, it can be seen that with a container blank on each mandrel 80 each of the machine's stations will perform a selected operation on the blank positioned at that station simultaneously with the operation of all the other machine stations; and that each of the mandrels will, in turn, be fed in sequence to each of the machine stations so that the necessary forming operations can be performed on each of the container blanks.

CONTAINER ERECTING MECHANISM

In accordance with the invention, container blank erecting means are provided at station "A" for erecting a flattened container blank into open-ended tubular form and for feeding the opened blank onto a mandrel assembly 80 on spindle 70. As embodied and as best shown in FIGS. 2 and 6, container blank erecting means 102 is located in the lower rear quadrant of container forming mechanism 69 and is adapted to open a flattened container blank and feed it onto a mandrel 80 in registration with the erecting means. The location of the container blank erecting means is important to the overall concept of the present machine as will be more fully described below.

As best shown in FIG. 6, container blank erecting means 102 includes a basket 104 positioned on a plate 106 which is connected to supporting structure 66 of the machine. Plate 106 has an aperture 108 through which erected container blanks are fed onto a mandrel (not shown).

Basket 104 is designed to hold a stack of flattened container blanks of various sizes and includes a pair of spaced flanges 110 that expose a lower side surface of a container blank mounted within the basket. As best shown in FIG. 1, basket 104 is readily accessible through an opening 105 in the rear of the machine.

Mounted below flanges 110 and aligned with the same is a supporting member 111 attached to plate 106 and which is provided with a lower container retaining edge 112. Also mounted to plate 106 and located on the opposite side of the opening between supporting flanges 110 is a curved plate 114 which engages the side of a container as it is pulled out of basket 104 and erects or opens the same. An upper container retaining edge 116 is provided on plate 114.

The containers are removed from basket 104 and erected or opened into a square cross-sectional shape between upper and lower retaining edges 112 and 116 by means of a manifold 118 mounted on the end of a reciprocating actuator 120 for movement toward and away from the bottom of basket 104. Manifold 118 is provided with a plurality of suction cups 122 that are connected through a vacuum line to a suitable source of vacuum (not shown) to create suction in cups 122. Further, means (not shown) are provided for venting manifold 118 to the atmosphere to release the suction in cups 122 when necessary so that an erected container blank can be removed from between retaining edges 112 and 116.

An endless chain 124 is mounted to a retaining bracket 125 on plate 106 for movement in a direction parallel to the longitudinal axis of an opened container blank lying between edges 112 and 116. As best shown in FIG. 6, endless chain 124 includes a pair of lugs 126 for engaging an upstanding edge of a bottom closure panel 14 of a container blank that has been opened and is being held between retaining edges 112 and 116 to push the container blank out of the edges and onto a mandrel assembly 80 located in registration with the erecting means.

The various operating parts of the container blank erecting means with the exception of the endless chain are described in detail in the Austin et al U.S. Pat. No. 3,364,826 referred to above and the disclosure of this patent is incorporated herein by reference.

Briefly, and in operation, suction is passed to manifold 118 and actuator 120 is actuated by the machine cycling means to advance manifold 118 toward the bottom side of a container blank held within basket 104. After contact, the manifold is retracted whereby the container blank, held to the manifold by the suction in cups 122, is pulled over curved plate 114 to open the container into a rectangular cross section. As the blank is pulled further down, it continues to open until it is retained in a generally rectangular cross section between upper and lower retaining edges 112 and 116.

The machine cycling means then releases the vacuum in cups 122 and simultaneously actuates endless chain 124 to bring one of the lugs 126 into contact with a bottom closure panel 14 on the opened container blank. After contact, the lug pushes the container out from between retaining edges 112 and 116 and onto a mandrel 80 in registration with that station. As the container is pushed onto the mandrel, the top

closure panels 16 arrest movement of the container blank by engagement with either the fingers 98 or 100 on the mandrel depending upon the length of the container.

BOTTOM FORMING MECHANISM

In accordance with the invention and after an opened container blank has been fed onto a mandrel 80, the machine cycling means rotates spindle 70 upwardly and in a counterclockwise direction as shown by arrows 128 in FIGS. 2 and 3, to bring the container blank into registration with bottom breaking station "B" of the container forming mechanism.

As embodied, this station includes a bottom panel breaking means, shown generally as 130, for breaking inwardly the bottom closure panels 14 of the container blank as it is mounted on a mandrel 80. The structure of the bottom panel breaking means does not form a part of the present invention and is described in detail in our copending application, Ser. No. 778,135 filed Nov. 22, 1968, now U.S. Pat. No. 3,593,625, and entitled Bottom Pre-Breaking Mechanism for Carton Forming Machine, the disclosure of which is hereby incorporated by reference.

Briefly and as shown in FIGS. 7 and 8, bottom panel pre-breaking means 130 includes a pair of inner fingers 132 which operate with a scissors-type action pivoting about points 133. Fingers 132 are moved toward a container 10 on a mandrel 80 under the action of a cylinder 134 actuated and controlled by the machine cycling means and engage bottom gusset panels 18 of the container blank and bend them along their fold lines. An outer pair of bars 135 mounted on arms 136 are also brought into contact with bottom closure panels 20 in a step sequence with the fingers 132. As the fingers 132 move toward the container, cams 137 ride through cam tracks 138 in arms 136 and pivot the bars 135 about points 133' to break inwardly the fold lines of these closure panels. The action of bars 135 is in a plane perpendicular to the plane of operation of fingers 132 so that the combination of bars and fingers engage both pairs of bottom closure panels 14.

The next two (2) succeeding stations "C" and "D" on supporting structure 66, to act on a container blank as it is rotated in step by spindle 70, are heating means for heating the plastic coating on the bottom closure panels of a container blank. As embodied, the heating means comprises gas burners 140 at first heating station "C" and at second heating station "D." Burners 140 are only shown generally in FIG. 2 in that they are conventional units and are positioned on structure 66 in a plane generally perpendicular to a mandrel 80 at that position for the most effective heating of the container panels. The gas burners are slidably mounted to supporting structure 66 so that they can be positioned toward and away from the ends of the bottom closure panels depending upon the length of the container blank being used. As is well known to those skilled in the art, the heat generated by the combination of the two (2) burners 140 in combination with the dwell time that the container remains at each heating station should be sufficient to put the thermoplastic coating on the bottom closure panels in a soft condition for bonding at a subsequent sealing station.

After the panels on the bottom of the container are softened, the machine cycling means rotates spindle 70 to bring the bottom closure panels into engagement with a pair of folding rails 142 and 144 positioned on either side of the path of rotation of the container and connected to the supporting structure immediately after the second heating station "D" and before the next succeeding machine station.

As best shown in FIG. 9, folding rails 142 and 144 converge towards each other as they approach the next operating station "E" and outer rail 144 is raised slightly above inner rail 142 so that inner rail 142 will act on tuck-in bottom closure panel 20' ahead of rail 144 which acts on tuck-out bottom closure panel 20" to insure proper folding of the bottom closure panels. Further rotation of spindle 70 then brings the folded bottom closure panels into registration with a bottom sealing means at station "E."

In accordance with the invention, pressure sealing means are provided at the next two succeeding work stations "E" and "F" for sealing the heated and folded bottom closure panels of the container blank to provide a sealed bottom to the container. As embodied, and as best shown in FIGS. 9 and 10, the pressure sealing means at both stations includes a press plate 148 which is secured to the shaft of a hydraulic cylinder 149 for reciprocation toward and away from the end cap 92 of a mandrel 80 located at that station. Cylinder 149 is mounted on supporting structure 66 and is actuated and controlled by the machine cycling means. Press plates 148 include internal passages (not shown) connected to a suitable source of cooling water through a conduit 150 to permit cooling water to flow through the press plate and cool the heated flaps to increase efficiency of the sealing operation.

When a mandrel is indexed in registration with the pressure sealing means, the machine cycling means advances press plate 148 toward the folded bottom panels, which have been placed in folded position by the rails 142 and 144, and presses the panels against end cap 92 to seal the bottom of the container closed and form a liquid-tight seal. As is well known to those skilled in the art, the pressure applied by press plates 148 in combination with the cooling of the heated bottom closure panels and the dwell time that the container remains at each station should be sufficient to seal the container shut.

Preferably, and as shown in FIG. 12, the outer surface of both press plates 148 are provided with channels 150 and 151 to provide clearance for the thickened portions of the container bottom caused by the overlapping ends of the bottom closure panels 20 and side seam 54 of the container body, respectively, as the plates 148 are pressed onto the folded bottom closure panels.

TOP BREAKING MECHANISM

In accordance with the invention, top closure panel breaking means are also provided at second sealing station "F" to break inwardly top closure panels 16 of the container blank.

As embodied, the top closure panel breaking means comprises a pair of breaking assemblies 152 and 154 positioned on either side of a mandrel (not shown) to engage the top panels 16 of a container blank posi-

tioned at that station. Breaking assemblies 152 and 154 are identical in form and only one will be described in detail, it being understood that the other has the same parts and functions in a like manner.

As best shown in FIGS. 10 and 11, each breaking assembly includes a guide flange 156 mounted to supporting structure 66 of the machines and includes an elongated guide member 158. Guide member 158 mounts a supporting plate 160 having a recess 162 which fits over guide member 158 and is slidably mounted thereon. A clamping bolt 164 extends through an aperture in supporting plate 160 and engages the guide member 158 to clamp supporting plate 160 in the desired location. A breaking finger 168 is pivotally mounted to supporting plate 160 at 170 and includes a lever arm 172 integral with finger 168 and extending in an opposite direction from pivot point 170.

In accordance with the invention, means are provided for operatively connecting press plate 148 with breaking finger 168 so that the finger 168 is actuated by reciprocal movement of the press plate. As embodied, this means comprises a rod 174 secured at one end to the side of press plate 148 and slidably mounted through an aperture 176 in a pivot block 177. Pivot block 177, in turn, is pivotally mounted to the outer end of lever arm 172 at 178. A clamping bolt 179 extends through block 177 to secure the block to rod 174 in the desired location.

In operation, clamping bolts 164 and 179 on each breaking assembly 152 and 154 are loosened and the breaking assemblies are slid along guide flanges 158 and rods 174 until the breaking fingers 168 on each assembly are adjacent the top closure panels of the container. Bolts 164 and 179 are then tightened in place. Thus, as press plate 148 at station "F" is advanced toward cap 92 by the machine cycling means, rods 174 will transmit this reciprocating motion to blocks 177 causing them to move outward and pivot breaking fingers 168 about point 170 toward each other and the top closure panels of the container blank. Thus, fingers 168 will be pivoted simultaneously with operation of the press plate toward each other from either side of the mandrel to pre-bend the top closure panel over the edges 82 or 96 of the mandrel depending on the size of the container.

Upon subsequent reciprocation of the press plate 50 away from the mandrel end cap 92 and retraction of rods 174, fingers 168 will pivot away from the mandrel and the container so that the container blank is then free for index to the next succeeding machine station.

In smaller size containers, that is, half pint to quart size, the gusset panels 18 of bottom panels 14 and the gusset panels 40 of top panels 16 are rotated 90° from each other. In larger size containers, however, and as shown in FIG. 28, the gusset panels of the top and bottom closure panels are on the same side of the container. Thus, the breaking fingers 168 will act with the smaller containers on the gusset panels 40 of the top closure panels 16 and with the larger containers on the roof panels 42.

CARRIER DISCHARGE MECHANISM

After the mandrels leave second bottom press and top pre-break station "F," they are moved to a con-

tainer removal station "G." In accordance with the invention and in combination with the location of the preceding work stations as described above, the container removing station is located in a lower quadrant of the path of rotation of spindle 70, and preferably in the opposite lower quadrant from container blank erecting station "A," so that the bottom formed containers will be discharged from the mechanism in a downwardly inclined direction of substantially 45° with respect to horizontal.

As best shown in FIGS. 13-15, container removing means are provided at container removal station "G" for sliding a bottom formed container off of the mandrel in a downwardly inclined direction. As embodied, this means comprises a pair of endless chains 180 mounted for translation between a drive sprocket 181 and an idler sprocket 182 in a direction generally parallel to the longitudinal axis of a mandrel 80 at that station. Each chain and its associate sprockets are mounted on a plate 184 on opposite sides of mandrel 80 and an aperture 185 is provided in plate 184 to permit the mandrel to pass through the station after a container has been removed. The shoulder halves 88 of the mandrel 80 have been deleted from FIGS. 13-15 for the sake of clarity.

As best shown in FIG. 13, a first pair of opposed lugs 186 are mounted to each chain 180 for engaging either the top closure gusset panels 40 or roof panels 42 depending on the container size of a container blank positioned on a mandrel at the container removal station.

In operation, and after a mandrel has been indexed into position at container removal station "G," endless chains 180 are rotated simultaneously and in opposite directions by the machine cycling means, as shown by arrows 187, so that opposed lugs 186 will translate down the length of mandrel 80 toward its end cap 92 to push a container blank off of the mandrel. Since the chain lugs need only travel approximately half the length of the chain to push a container blank off a mandrel, a second pair of opposed lugs 188 are also mounted to endless chains 180 in spaced relationship with first opposed lugs 186. Thus, after lugs 186 have pushed a container off the mandrel, lugs 188 will be in position for removing the next succeeding container blank indexed to the container removal station.

As best shown in FIGS. 13 and 14, a second idler sprocket 189 is provided for each chain 180 to keep the direction of travel of the lugs generally parallel to the axis of the mandrel until they near end cap 92. After passing sprockets 189, the lugs are pulled back away from the mandrel and the container as the chains turn around drive sprockets 181, and slots 190 are provided in end cap 92 of each mandrel 80 to provide clearance for these lugs.

In accordance with the invention, a chute 192 is mounted to supporting structure 66 below mandrel 80 at the container removal station and is inclined in a plane generally parallel to the longitudinal axis of the mandrel. The chute receives the container after it has been removed from the mandrel and holds the container in a downwardly inclined direction.

Preferably, and to accommodate containers having varying cross-sectional dimensions, chute 192 is releasably secured to supporting structure 66, for example, by a locking wheel 194 so that chutes of varying

widths can be interchanged depending on the cross-sectional dimensions of the container being processed.

After a container has been removed from a mandrel 80 at container removing station "G," the machine cycling means indexes the mandrel, now free of the container, to a machine cooling station "H" where means are provided for cooling end cap 92 of the mandrel assembly. As embodied, this means comprises a press plate 196, similar to sealing press plates 148, and is mounted to supporting structure 66 for vertical reciprocation toward and away from end cap 92. Press plate 196 includes internal passages (not shown) connected to a suitable source of cooling water to permit cooling water to flow through the press plate and cool end cap 92 as the press plate is brought into contact with the end cap at the machine cooling station.

Finally, the machine cycling means indexes the empty and cooled mandrel from cooling station "H" back to container erecting station "A" for the next machine cycle.

CONTAINER TRANSFER MECHANISM

In accordance with the invention, transfer means generally 198, are provided for arresting movement of the bottom formed container as it passes through chute 192 after the container has cleared mandrel end cap 92 and for gripping and pivoting the discharged bottom formed container to an upright position.

As embodied and as best seen in FIGS. 16, 17, and 17A, transfer means 198 includes a transfer arm 200 mounting a suction cup 202 at one end and including an internal passage (not shown) connecting suction cup 202 with a suitable source of vacuum (not shown). Arm 200 is slidably journaled in a movable block 206 for adjustment in axial direction and a clamping bolt 208 is threaded through block 206 to clamp arm 200 in the desired location.

As best shown in FIGS. 16 and 17A, arm 200 extends through block 206 and also through block 209 secured at 210 to the lower end of block 206. Block 209, in turn, is journaled at either end at 211 in fixed supporting blocks 212 for rotation about an axis 213. Block 212 is secured at 212' to the frame structure 66 of filler mechanism 62.

In accordance with the invention, actuating means are provided for pivoting arm 200 and container 10 between its first position coextensive with the longitudinal axis of mandrel 80 and container removal station "G" and its upright position. As embodied, this means comprises a hydraulic cylinder 214 mounted to the supporting structure 66 of the filler mechanism and having its piston rod 215 pivotally connected to movable block 206.

In operation and depending upon the length of the particular container being used, the length of arm 200 extending above block 206 is adjusted to position cup 202 in the proper location, and the arm is secured in place by bolt 208. The machine cycling means then actuates hydraulic cylinder 214 to push blocks 206 and 209 and pivot arm 200 about axis 213 to its first position as shown in phantom in FIG. 16. In this position, suction cup 202 lies adjacent the bottom of receiving chute 192. After discharge of a container from the forming mechanism and its receipt by the transfer arm, the machine cycling means first pulls a vacuum on cup

202 to grip the bottom of container 10 to the arm. The machine cycling means then reactivates cylinder 214 to pivot arm 200 and attached container 10 through an angle of less than 90°, e.g. substantially 45°, to its second and substantially upright position where it is now in place for feeding through the filling mechanism as will be further described below.

In addition to transferring the container from the forming mechanism to the filling mechanism, it is sometimes also necessary, particularly with smaller size containers, to rotate the container 90° about its axis so that the top closure panels are in the proper position for sealing in the filling mechanism. Rotation of the container is shown schematically in FIG. 3. With larger size containers, however, where the gusset panels of the top closure panels are 90° out of phase with the smaller containers, it is not necessary to rotate the container as it is being transferred to the filling mechanism.

Accordingly, selective operating means are further provided for rotating arm 200, 90° about its axis as the arm pivots between its first container receiving position and its second upright position. As embodied, and as best shown in FIG. 17, this means comprises a follower arm 216 fixed to arm 200 for rotation therewith and mounting a fixed post 218 and a removable pin 220 extending in an aperture 221 in the arm. A bias spring 222 is connected to post 218 at one extremity and to post 224 mounted on a bracket 226' attached to movable block 206. In addition, a fixed cam rod 226 projects upwardly from fixed supporting block 212 and provides a cam surface to cooperate with follower arm 216.

In operation, and when pin 220 is inserted into aperture 221, it can be seen that arm 200 will not rotate as it pivots between positions, the pin 220 acting against block 206 preventing rotation under the influence of spring 222 when arm 200 is in its first inclined position and rod 226 acting against arm 216 to prevent rotation when arm 200 is in its second vertical position. When pin 220 is removed, however, and arm 200 is pivoted to its inclined position, it can be seen that follower arm 216 will move to the right around rod 226 and turn arm 200 clockwise under the influence of spring 222 acting on post 218. The stroke of piston 214 is such that arm 200 will have rotated 90° about its axis in a clockwise direction by the time it reaches its first position adjacent chute 192. Upon retraction of piston 214 and movement of arm 200 back to its vertical position, fixed rod 226 will force follower arm 216 and transfer arm 200 to rotate back to original position 90 degrees out of phase with its inclined position, thus rotating the container the required 90 degrees.

As noted above, however, when it is not necessary for the container to be rotated, pin 220 is inserted back into follower 216 to prevent right rotation of follower 216 as the block and arm 200 move past fixed rod 226 under the action of the hydraulic cylinder.

When arm 200 reaches its upright position, the machine cycling means disconnects the vacuum to cup 202 permitting the container to be released and allowing the arm to swing back to its original position free of the container.

CARRIER FORMING MECHANISM

Preferably, and as shown in FIG. 1, the filling mechanism 62 that is used in conjunction with con-

tainer-forming mechanism 60 includes a feeding mechanism, generally 228, for receiving the bottom-formed containers in an upright position from transfer arm 200 and for moving the containers with a step-by-step indexing motion to bring them into registration with the machine's filling and sealing operations. A filling mechanism capable for use with the container-forming mechanism of the present invention is shown and described, for example, in the above mentioned U. S. Pat. No. 3,465,494 to Garrett et al. Reference should be made to this patent for more detailed description of some of the operating parts which are common to the filling mechanism 62 of the present invention.

As best shown in FIGS. 1 and 2, the filling mechanism of the present invention conventionally includes frame structure 66 and is provided with a table top 232 mounting a pair of rods 234 which support the various components of the filling mechanism. These components include in sequence a filling means 240, a heating means 242 for heating the top closure panels of the bottom-formed containers, a pair of converging guide rails 244 (see FIG. 3) located under the heating means for closing the container's top closure panels to form a gabled top to the container, and a sealing means 246 to heat-seal the folded top closure panels closed.

Briefly, filling means 240 includes a supply tank 248 and a plurality of filling stems 250 extending downwardly from the supply tank and directly above a container being moved with step-by-step indexing by the feeding mechanism 228. A dispensing valve 252 is provided at the end of each filling stem 250 for controlling the flow of liquid passing through that stem into a container.

As best shown in FIG. 2, a plurality of filling stems 250, five (5) of which are shown in the drawing, are provided instead of just one filling stem to increase the overall speed of the filling operation. Thus with half-gallon containers, for example, the containers can be indexed through 5 stages of filling at the 5 filling stems 250, each container receiving one-fifth of its total volume at each station instead of receiving all of its volume at one station. Further, the use of the plurality of filling stems accommodates the filling mechanism to other volume-sized containers. Thus, the volume of flow from each filling stem can be decreased or some of the stems can be de-actuated for use with smaller sized containers.

The heating means 242 is positioned subsequent to filling means 240 and includes a heating element and a suitable control means (not shown) for controlling the amount of heat given off by the heater assembly. The heater is pivotally mounted on one of the rods 234 and rests on the other rod so that it may be pivoted away from its heating location above the containers when desired.

Also mounted on the rods 234 are the pair of converging guide rails 244, see FIG. 3, which are positioned below heater means 242 and extend in a converging direction toward the sealing means 246. Guide rails 244 fold top closure panels 16 of the paperboard containers during heating to place them in position for closing by the sealing means. Guide rails 244 are also hollow and connected to a suitable source of cooling water (not shown) to temper the heated closure panels before the container passes to the pressure sealing means 246.

Sealing means 246 is positioned adjacent heater means 242 and includes a pair of sealer jaws 266 for bonding the sealing flaps of the top closure panels together. Jaws 266 are connected through suitable mechanical linkage to the piston rod 268 of a hydraulic cylinder 270 mounted to a frame 272 which is supported by rods 234 (see FIG. 2).

In operation, and after a container has been indexed in registration with sealing means 246, sealer jaws 266 are pivoted toward each other and in a direction transverse to the path of travel of the containers and the length of sealing flaps 50 to seal the top of the container closed.

As shown in FIGS. 1 and 2, a plurality of sealing means 246, two (2) of which are shown in the drawing, are provided to permit an increase in the speed of operation without increasing the risk of an improperly sealed container. Hence, both of the sealing mechanisms will act on all containers and the total sealing time will be equal to the sum of the individual time spent at each sealing station.

At the opposite or output end of filling mechanism 62, the filled and sealed containers are discharged onto an accumulating table 274 adapted to receive in a row a specific number of containers depending on their cross-sectional area. When the foremost container reaches the limit switch 276 (see FIG. 3) switch 276 activates a pusher 278 to move the entire row of filled containers over one row, thereby allowing another row of containers to advance one by one into position. The cycle is continued in this manner up to the capacity of the table.

FEEDING MECHANISM

In accordance with the present invention, a new and improved feeding mechanism is provided for achieving more accurate and efficient filling and sealing of the containers and for more readily accommodating containers of various sizes.

As embodied, and as best shown in FIGS. 18-25, this means comprises a pair of endless chain assemblies 290 and 292 arranged in spaced, parallel relation on either side of the required path of movement of the containers through filling mechanism 62. Each chain assembly includes an upper and lower endless chain 294 and 296, respectively, (see FIGS. 19 and 22) a pair of upper and lower drive sprockets 298 mounted for rotation therewith to a vertical drive shaft 300 at the discharge end of the filling mechanism and a pair of upper and lower idler sprockets 302 mounted for rotation about a vertical idler shaft 304 at the receiving end of the filling mechanism. A plurality of guide rails 306 are provided between the drive and idler sprockets to maintain the chains in a substantially horizontal position as it passes between the sprockets.

In accordance with the invention, a plurality of container engaging blocks 310 (see FIG. 25) are mounted between upper and lower chains 294 and 296 of each chain assembly 290 and 292 in longitudinal spaced relationship and in transverse registration as shown, for example, in FIGS. 18 and 19. Each of the container engaging blocks 310 is identical and only one will be described in detail, it being understood that the other blocks are constructed and function in combination in a similar manner.

As best shown in FIGS. 19 and 22-24, conveyor blocks 310 extend in a substantially vertical direction with the top of the block being connected to a link 311 of upper chain 294 and the bottom of the block being connected to a similar link of lower chain 296 for movement therewith.

In accordance with the invention, and as best shown in FIGS. 23-25, each conveyor block 310 is provided with corner means for engaging one of the corners of an open and upright container. A grouping of four container blocks (see FIGS. 23 and 24), two on each chain assembly, are spaced so that four corresponding corner means on four adjacent blocks snugly embrace the four corners of a container 10 and maintain the container in an erect position as it is moved with step-by-step indexing through the machine's filling and sealing operations.

As embodied and with reference to FIG. 23, the corner means comprises a niche 312 on a trailing face 314 of one conveyor block 310 and a corresponding niche 316 on the leading face 318 of the next succeeding conveyor block 310' on chain assembly 292 for engaging two adjacent corners of a container blank 10.

Likewise, two adjacent conveyor blocks 310A and 310A' on chain assembly 290 and in transverse registration with blocks 310 and 310' on chain assembly 292 have niches 312' and 316', respectively. Niches 312' and 316' correspond to niches 312 and 316 and are spaced therefrom a distance equal to the width of a container being used for engaging the opposite two corners of the container blank. Thus, in such a feeding mechanism a container blank is snugly embraced by four (4) cooperating conveyor blocks and is maintained in an erect position by the blocks as the chain assembles move the blocks through the filling mechanism.

During travel through the filling mechanism, the base of the containers slide over a rail 320 on the top of table 232. To accommodate containers of varying heights, rail 320 is vertically adjustable and is connected through suitable mechanical linkage to a crank wheel 321 for adjustment by the operator.

In operation, and as best shown in FIGS. 18, 19 and 22, the movement of chain assemblies 290 and 292 is synchronized with container forming mechanism 60 and transfer arm 200 so that an aligned pair of blocks 310 are in position to receive a container 10 being transferred to the filling mechanism. Hence, as transfer arm 200 pivots to an upright position, it throws the two (2) leading corners of the container into the niches 312 and 312' on the trailing faces 314 of an opposed pair of blocks 310 and 310A.

As best shown in FIG. 22, the next succeeding pair of opposed blocks 310' and 310A' are rounding idler sprockets 302 and, therefore, will not interfere with the insertion of the container into the feeding mechanism.

In accordance with the invention, means are provided for momentarily arresting movement of the container to square up the side walls of the bottom formed container as it is being transferred to the filling mechanism and thereby insure its proper insertion into the feeding mechanism.

As embodied and as best shown in FIGS. 22 and 22A, this means comprises a pair of spring-loaded arms 322 pivotally mounted at 323 to a plate 324. Each plate

324 is affixed to the top of an idler shaft 304 at the loading end of the filling mechanism and a stop block 325 is mounted to the top of each plate. Further, each arm 322 is provided with a fixed post 326 and a bias spring 327 is connected between posts 326 and stop blocks 325 to keep the arms in an at-rest position against the blocks.

As best shown in FIG. 22A, each plate 324 is mounted to shafts 304 so that the trailing surface 400 of a container engaging extension 402 on each arm in its at-rest position is located above but slightly forward of the niches 312 and 312' on the pair of conveyor blocks 310 and 310A that are in position to receive the container from the transfer mechanism.

In addition, pushing means are provided for pushing the top of the container against the arms extensions 402 and into the pair of conveyor blocks, and for holding it in this position until the next succeeding pair of conveyor blocks, 310' and 310A' are brought into engagement with the trailing corners of the container. As embodied, and as best shown in FIGS. 19 and 22, this means comprises a flipper bar 404 pivotally connected to the piston 406 of a hydraulic cylinder 408 which is mounted to the supporting structure 66 above the loading end of the filling mechanism.

Thus, in operation and as arm 200 of the transfer mechanism flips a container up into the feeding mechanism, the top of the leading corner of the container will first contact an extension 402 on an arm 322 (see FIG. 22A). The machine cycling means then actuates cylinder 408 to pivot bar 404 down into engagement with the trailing side of the container and push the container against the arms extensions 402 to open up or remove the "diamond shape" from the top of the bottom formed container. Immediately thereafter, arm 200 and bar 404 push the squared container into the niches 312 and 312' on conveyor blocks 310 and 310A.

As the chain assemblies move down the length of the filling mechanism, the bar 404 continues to move to hold the container in this position until the blocks 310' and 310A' are brought around into engagement with the trailing corners of the container. The container is then held by the four blocks in a square position, as shown in FIG. 23, and the bar 404 is flipped back to an out-of-the-way position. As the feeding mechanism is indexed forward, the blocks pull the container through spring-loaded arms 322, the arms pivoting to the position as shown in phantom in FIG. 22A and then back to their original at-rest position under the influence of springs 327.

As best shown in FIGS. 23-25, leading and trailing faces 318 and 314, respectively, of the blocks immediately adjacent the niches are slanted to prevent interference with the container as it is thrown into the feeding mechanism or as the blocks are brought around into engagement with the trailing corners of the container.

In accordance with the invention, a plurality of corresponding leading and trailing corners are provided on each block 310 and means are provided for adjusting chain assemblies 290 and 292 toward and away from each other to accommodate containers of different base sizes without disturbing the filling mechanism's synchronization with the forming and transfer mechanisms.

As embodied, this comprises a second niche 328 on the trailing face 314 of each conveyor block 310 and a corresponding niche 329 on the leading face 314 of each conveyor block 310 and a corresponding niche 329 on the leading face 318 of the next succeeding conveyor block 310'. As shown in FIG. 23, the distance between niches 328 and 329 is greater than between niches 312 and 316 and is for use with containers of larger base sizes. The distance between corresponding niches 328 and 328' and 329 and 329' on opposed blocks 310 and 310A and 310' and 310A', respectively, however, is less and, therefore, the means for adjusting the chain assemblies with respect to each other is provided to space opposed blocks the proper distance from each other for the larger sized containers.

As embodied, this means comprises blocks 330 and 331, see FIG. 21, for rotatively supporting the drive shafts 300 of both chain assemblies 290 and 292 and supporting blocks 332 and 333 for rotatively supporting idler shafts 304, see FIGS. 19 and 22. As best shown in FIGS. 19, 21, and 22, each block 330-333 is slidably mounted on a guide flange 334 on table top 232 for movement in direction transverse to the movement of the container through the filling mechanism. An adjusting rod 335 is rotatively supported in blocks 336 and 338 on table top 232 and is provided with a crank wheel 340 for rotation in either direction by the operator of the machine. As best shown in FIG. 21, the left-hand portion of adjusting rod 335 is provided with a right-handed thread which is received by a suitable threaded aperture 342 in block 330 and the right-hand portion of the rod is provided with left-handed threads that is received by a threaded aperture 344 in block 331. As best shown in FIG. 22, a similar adjusting rod 350 having a crank wheel 352 and rotatively supported by blocks 354 and 356 on table top 232 is threaded through idler supporting blocks 332 and 333 in a similar manner.

Thus, as adjusting rods 335 and 350 are rotated in a given direction, the blocks 330-333 slide on flange 334 and chain assemblies 290 and 292 are moved toward or away from each other to provide the proper distance between the corner means on conveyor blocks 310.

As best shown in FIG. 21, drive shafts 300 of both chain assemblies 290 and 292 extend through table top 232 and are provided with bevel gears 354 on the portion extending beneath the table. A main drive shaft 356 is rotatively mounted in a center bracket 358 and end brackets 360 of table 232. A drive sprocket 362 is mounted on drive shaft 356 and is connected to a suitable source of power (not shown), such as an electric motor, that is controlled by the machine cycling means for intermittent movement. A pair of smaller bevel gears 364 are rotatively fixed on a drive shaft 356 in meshing engagement with each of the bevel gears 354 but are keyed to the shaft to permit the gears 364 to slide longitudinally of the shaft as the chain drive shafts 300 are moved toward and away from each other.

Thus, to adjust the feeding mechanism for use with smaller sized containers, as shown in FIG. 23, or for use with larger sized containers, as shown in FIG. 24, wheels 340 and 352 are turned in the proper direction to move both ends of each chain assembly away from each other until the corresponding niches 328 and 328' and 329 and 329' are spaced apart the same distance as between 328 and 329. As shown in FIGS. 23 and 24,

the axis 366 of the containers is always in the same place regardless of the size of the container and, thus, it is not necessary to adjust the synchronization of the feeding mechanism or its operating speed when changing between container sizes.

To support chain assemblies 290 and 292 in operating position and to prevent the sheer weight of the assemblies from binding on guide flanges 334 as the assemblies are moved toward and away from each other, each of these assemblies is supported by a pair of fixed center posts 370 and 372 mounted to the top of table 232, see FIGS. 18 and 20A. An upper and lower sleeve 374 and 376 are mounted on each rod 370 and 372 and are held in vertical position by a locking ring 378 but are permitted to pivot about the axis of the center posts. Upper and lower supporting arms 380 and 382, respectively, are journaled in one end in sleeves 374 and 376 on post 372 and at the other end in similar sleeves 384 and 386 similarly mounted on idler shaft 304, see FIG. 19. As shown in FIG. 19, the ends of arms 380 and 382 are threadably engaged at 388 with sleeves 384 and 386 to provide adjustment between fixed center post 372 and the sliding idler shaft 304.

Likewise, a second pair of upper and lower supporting arms 380' and 382' extend outwardly from center post 370 to support the drive shaft end 300 of each chain assembly in a similar manner. Thus, supporting arms 380 and 382 in combination with fixed center posts 370 and 372 support the outer extremities of chain assemblies 290 and 292 in a fixed vertical position off the top of table 232 and guide flange 334 while permitting independent or simultaneous transverse movement of both ends of the chain assemblies.

The upper and lower chain guide rails 306 are mounted at their ends to a block 390, see FIG. 20, which in turn is mounted on supporting arms 380 and 382 so that the chain and chain guides move in and out with adjustment of the chain assemblies.

The present invention, therefore, provides an improved container fabricating machine for forming, filling, and sealing tubular container blanks. As such, and as fully described above, the machine has simplified and made more positive the mechanical operations of the machine over prior art devices, resulting in an increase in the speed, accuracy, and economy of the entire packaging operation.

The invention in its broader aspects is not limited to the specific details shown and described, and departures may be made from such details without departing from the principles of the invention and without sacrificing its chief advantages.

What is claimed is:

1. In a machine for forming, filling, and sealing tubular container blanks having top and bottom foldable closure panels, a container forming mechanism comprising:

- a. a supporting structure;
- b. a spindle mounted to the structure for rotation about a horizontal axis;
- c. means for rotating said spindle with an indexing motion;
- d. a plurality of mandrels mounted on the spindle and extending radially therefrom for receiving and holding a container blank in an open position;

e. means defining a plurality of machine stations located on the structure and spaced about the axis of rotation of the spindle for sequential registration with said mandrels, said machine station means including:

- i. container blank erecting means for erecting a blank into open-ended tubular form and for feeding said opened blank onto a mandrel,
  - ii. container bottom forming means for breaking, heating, folding, and sealing the bottom closure panels of the opened container of the mandrel, and
  - iii. container removing means located in a lower quadrant of the path of rotation of the spindle for removing a bottom formed container off the mandrel in a downwardly inclined direction; and
  - f. transfer means for receiving said container removed from the mandrel and for gripping and pivoting said container through an angle of substantially 45° to an upright position, said transfer means comprising:
- i. a transfer arm pivotally mounted for movement between a first position substantially aligned with the inclined axis of discharge of containers and a second upright position,
  - ii. a suction cup mounted on one end of the arm for receiving and gripping the bottom of a container as it is removed from the container forming mechanism,
  - iii. actuating means for pivoting the arm and the container between said first and second positions, and
  - iv. means for selectively rotating the arm and cup 90° as it moves between said first and second positions to rotate the container about its longitudinal axis.

2. The machine of claim 1, in which the container blank erecting means is located in a lower quadrant of the path of rotation of the spindle and the container removing means is located in the opposite lower quadrant of the path of rotation of the spindle.

3. The machine of claim 1, in which the longitudinal axis of a mandrel in registration with said container removing means is inclined at an angle of approximately 45 degrees to the horizontal and the container removing means removes the container from the mandrel in a downward direction coextensive with the axis of the mandrel.

4. The machine of claim 3, in which the container removing means comprises container engaging means for pushing a bottom-formed container off the mandrel and a downwardly inclined chute for receiving and guiding the container as it is removed from the mandrel.

5. The machine of claim 4, in which the container engaging means comprises an endless chain whose direction of travel is parallel to the axis of the mandrel and having a container engaging lug for pushing the container off the mandrel.

6. The machine of claim 5, including a pair of endless chains on either side of the mandrel.

7. The machine of claim 1, in which the means for rotating the arm includes fixed cam means, a cam follower connected to said arm, and a biasing spring for rotating the cam follower and the arm as the arm pivots

between said first and second positions, and locking means selectively locking the cam follower in a fixed position to prevent rotation of the arm.

8. The machine of claim 1, in which the arm is axially adjustable to accommodate containers of varying lengths. 5

9. The machine of claim 1, in which the bottom forming means includes:

- a. bottom panel breaking means for breaking inwardly the bottom closure panels of the container; 10
- b. heating means for heating the broken bottom closure panels;
- c. folding means for folding the heated closure panels to form a bottom to the container; and
- d. a pressure sealing means to seal the folded bottom closure panels shut. 15

10. The machine of claim 9, including top closure panel breaking means operative simultaneously with said pressure sealing means to break inwardly the top 20 closure panels of the container blank.

11. The machine of claim 10, in which the machine has eight (8) radial arms and eight (8) correspondingly spaced machine stations, said container blank erecting means being located at a first machine station, said bottom panel breaking means being located at the second station, said heating means being located at the third and fourth stations, said folding means being located between the fourth and fifth stations; said pressure sealing means being located at the fifth and sixth stations, and the container removing means being located at the seventh station. 25, 30

12. The machine of claim 11, including pressure cooling means located at the eighth station. 35

13. A machine for forming, filling, and sealing tubular container blanks having top and bottom foldable closure panels, including a container forming mechanism comprising:

- a. a supporting structure;
- b. a spindle mounted to the structure for rotation about a horizontal axis;
- c. means for rotating said spindle with an indexing motion;
- d. a plurality of mandrels mounted on the spindle and extending radially therefrom for receiving and holding a container blank in an open position; 45
- e. means defining a plurality of machine stations located on the structure and spaced about the axis of rotation of the spindle for sequential registration with said mandrels, said machine station means including:
  - i. container blank erecting means for erecting a blank into open-ended tubular form and for feeding said opened blank onto a mandrel,
  - ii. container bottom forming means for breaking, heating, folding, and sealing the bottom closure panels of the opened container on the mandrel, and
  - iii. container removing means located in a lower quadrant of the path of rotation of the spindle for removing a bottom formed container off the mandrel in a downwardly inclined direction;
- f. transfer means for receiving said container removed from the mandrel and for gripping and pivoting said container through an angle of substantially 45° to an upright position; and 65

g. a container filling mechanism having a feeding mechanism for receiving the container blanks in an upright position from the transfer means and for feeding the blanks with a step-by-step indexing motion successively into registration with filler means for filling the bottom formed containers and top sealing means for sealing closed the top closure panels said feeding mechanism comprising:

- i. a supporting surface for supporting the bottom of the containers along which the containers are advanced through the filling mechanism,
- ii. a pair of endless chain assemblies arranged in spaced parallel relation on opposite sides of the direction of travel of the container,
- iii. means for adjusting the chain assemblies toward and away from each other,
- iv. a plurality of conveyor blocks mounted on said chains in opposed transverse registration, each block of a first pair of opposed blocks having corner means for engaging a leading corner of a container and each block of the next succeeding pair of opposed blocks having corner means for engaging a trailing corner of the container,
- v. each of said blocks of said first pair also having similar corner means for engaging a trailing corner of the next preceding container and each of said blocks of the next succeeding pair having similar corner means for engaging a leading corner of the next succeeding container whereby the containers are firmly gripped by the corner means of adjacent pairs of opposed blocks as they move through the machine, and
- vi. each of said blocks further having a plurality of corresponding, leading, and trailing corner means for accommodating containers of different base sizes.

14. The machine of claim 13, in which corner means on adjacent pairs of opposed blocks are symmetrical about a vertical axis which is coextensive with the longitudinal axis of the different sized containers held by the blocks. 40

15. The machine of claim 13, wherein the transfer means pivoting the bottom-formed container into an upright position throws the container into one end of the feeding mechanism so that the leading corners of the container engage the corner means on the first pair of opposed blocks and thereafter the trailing corners of the container are brought into engagement with the corner means on the next pair of opposed blocks, said transfer means releasing the container after the container is engaged with the first pair of blocks. 50

16. The machine of claim 13, wherein the adjusting means comprises guide means for slidably mounting the chain assemblies to the filling mechanism and gear means for simultaneously moving the chain assemblies toward or away from each other. 55

17. The machine of claim 15, including means for squaring up the side walls of the container prior to engagement of the leading corners of the container with the corner means on the first pair of opposed blocks. 60

18. The machine of claim 17, in which the means for squaring up the side walls of the container includes a pair of spring-loaded arms for momentarily arresting movement of the container as it is pivoted into an upright position and pushing means for pushing the

container against the arms to square up the side walls of the container and for pushing the squared container into the corner means in the conveyor blocks.

19. The machine of claim 18, in which the pushing means also holds the container in engagement with said first pair of blocks after said transfer means releases the container and until the second pair of blocks is brought into engagement with the container. 5

20. The machine of claim 16, wherein each end of the chain assemblies is supported by a supporting arm 10 pivotally mounted to a fixed post that is located midway between the ends of the assemblies and each end having guide means and gear means for independent movement of the ends of the chain assemblies.

21. A transfer mechanism for a container fabricating machine for transferring bottom formed containers from a container forming mechanism to a filling mechanism, and in which the bottom formed containers are removed from the container forming mechanism in a downwardly inclined direction of substantially 45° with respect to horizontal said transfer mechanism comprising: 15

- a. a transfer arm pivotally mounted for movement between a first position substantially aligned with the inclined axis of the discharged container and a second vertical position; 25
- b. a suction cup mounted on the end of the transfer arm for receiving and gripping the bottom of a container as it is removed from the container forming mechanism;
- c. actuating means for pivoting the arm and the container between said first and second positions; and
- d. means for selectively rotating the transfer arm and the suction cup 90° as it moves between said first and second positions to rotate the container about 35 its longitudinal axis.

22. The transfer mechanism of claim 21, in which the means for rotating the transfer arm includes fixed cam means, a cam follower connected to said arm, and a biasing spring for rotating the cam follower and the arm as the transfer arm pivots between said first and second positions, and locking means selectively locking the cam follower in a fixed position to prevent rotation of the arm. 40

23. The mechanism of claim 21, in which the transfer arm is axially adjustable to accommodate containers of varying lengths. 45

24. In a machine for top filling and sealing containers, a feeding mechanism for advancing bottom-formed containers linearly with a step-by-step indexing motion into successive registration with the machine's operating stations, said feeding mechanism comprising: 50

- a. a supporting surface for supporting the bottom of the containers along which the containers are advanced through the machine;
- b. a pair of endless chain assemblies arranged in 55

spaced parallel relation on opposite sides of the direction of travel of the container;

- c. means for adjusting the chain assemblies toward and away from each other;
- d. a plurality of conveyor blocks mounted on said chains in opposed transverse registration, each block of a first pair of opposed blocks having corner means for engaging a leading corner of a container and each block of the next succeeding pair of opposed blocks having corner means for engaging a trailing corner of the container;
- e. each of said blocks of said first pair also having similar corner means for engaging a trailing corner of the next preceding container and each of said blocks of the next succeeding pair having similar corner means for engaging a leading corner of the next succeeding container whereby the containers are firmly gripped by the corner means of adjacent pairs of opposed blocks as they move through the machine; and
- f. each of said blocks further having a plurality of corresponding, leading, and trailing corner means for accommodating containers of different base sizes.

25. The machine of claim 24, in which the corresponding corner means on adjacent pairs of opposed blocks are symmetrical about a vertical axis which is coextensive with the longitudinal axis of the different sized containers held by the blocks.

26. In a machine for forming containers from a tubular container blank having top and bottom foldable closure panels and having a bottom panel pressure sealing station including a press plate movable toward and away from the bottom of the container, a top panel pre-breaking mechanism operated by and simultaneously with said pressure sealing means comprising:

- a. a pair of breaking fingers pivotally mounted in opposed relation adjacent an opposed pair of the top closure panels of the container; and
- b. means for operating said fingers including a lever arm connected to each finger and a pair of parallel rods, one end of each rod being connected to the press plate and the other end being connected to a lever arm whereby the fingers pivot in and out as the press head reciprocates to bring the fingers into engagement with the opposed top closure panels.

27. The mechanism of claim 26, in which the lever arm is slidable with respect to the rod and including means for securing the lever arm in a fixed position to the rod, and in which each of said fingers is pivotally mounted on a supporting block that is slidably mounted to a fixed structure on either side of the container to permit the adjustment of the top-breaking mechanism for various sized containers.
